(57) **CLAIM**

The ornamental design for a spray nozzle for a fire protection system, as described and shown.

DESCRIPTION

FIG. 1 is a perspective view of a spray nozzle, showing my claimed design, wherein the spray nozzle includes a barrel having four concentric grooves;

FIG. 2 is a front elevation view thereof;

FIG. 3 is a side elevation view thereof;

FIG. 4 is a bottom base view thereof;

FIG. 5 is a top plan view thereof;

FIG. 6 is a side elevation view of a spray nozzle according to an alternative design, the spray nozzle being substantially similar to that of FIG. 1, but having a barrel with one groove.

FIG. 7 is a side elevation view of a spray nozzle according to an alternative design; the spray nozzle being substantially similar to that of FIG. 1, but having a barrel with two grooves; and,

FIG. 8 is a side elevation view of a spray nozzle according to an alternative design, the spray nozzle being substantially similar to that of FIG. 1, but having a barrel with three grooves.
